Application April 15, 1957, Serial No. 652,899

11 Claims. (Cl. 53—40)

This invention relates to a method and apparatus for assembling rivets on a wire or similar mandrel.

An object of this invention is to provide an improved method and apparatus for threading rivets on a wire or similar member.

Another object of this invention is to provide an improved method and apparatus for assembling rivets upon a wire or similar member so that the assembly may be used in a riveting gun or similar device.

Still another object of this invention is to provide an improved method for assembling rivets upon a wire or similar member which is provided with an enlarged end member for retaining the rivets assembled thereon after a predetermined number of rivets are so assembled.

A further object of this invention is to provide an improved apparatus for assembling rivets upon a wire or similar member, said apparatus being constructed to assemble a predetermined number of rivets in each cycle of operation thereof.

A still further object of this invention is to provide an improved apparatus for assembling rivets on a wire, said apparatus being provided with wire gripping means that is shaped to grip the end portion of the wire and also to guide the rivets on to the end of the wire.

Another object of this invention is to provide an improved apparatus for assembling rivets on a wire, said apparatus being provided with jaw members shaped to expose an increasing length of the wire while simultaneously gripping the wire as the rivet is urged on to the end portion thereof.

Other and further objects of this invention will be apparent to those skilled in the art to which it relates from the following specification, claims and drawing.

In accordance with this invention there is provided a method and apparatus for assembling hollow rivets on a wire or similar mandrel so that such assemblies may be conveniently packaged, shipped and used in riveting guns. The mandrel is of the type provided with a rivet upsetting enlargement at one end thereof and further providing an elongated body portion upon which a plurality of hollow rivets may be threaded. The rivets are all threaded upon this mandrel in the proper direction so that when they are forced therefrom by the gun during the riveting operation, they are properly upset. During the assembly of the rivets upon this mandrel, they are first arranged in a file from which they are withdrawn one by one and placed upon the mandrel which is suitably supported to receive said rivets. After a predetermined number of rivets are placed upon the mandrel, an enlargement is placed or formed on the rivet receiving end of the mandrel whereby said rivets are held in assembled relation thereon.

The apparatus of this invention was constructed for the purpose of facilitating assembly of a predetermined number of rivets in a semi-automatic manner so as to increase the efficiency of the assembly and reduce the cost thereof.

Further features of this invention will be set forth in

2

the following specification, claims and drawing in which briefly:

Fig. 1 is a view in side elevation of an embodiment of this apparatus.

Fig. 2 is a plan view of this apparatus;

Fig. 2a is a fragmentary sectional view along the line 2a—2a of Figure 2;

Fig. 2b is a fragmentary sectional view along the line 2b—2b of Figure 2;

Fig. 2c is a fragmentary sectional view showing the support of the rivets over the wire mandrel;

Fig. 2d is a plan view of the mechanism shown in Fig. 2d;

Fig. 3 is a view in side elevation of the portion of the machine assembling the rivets on a wire mandrel;

Fig. 4 is a detail view showing the pneumatic drive of the rivet moving turret;

Figs. 5, 6 and 7 are sectional views of the mandrel gripping jaws illustrating the different positions of these jaws during the placing of a rivet on the mandrel;

Figs. 8 and 9 are additional views of the mandrel gripping jaws; and

Fig. 10 is a schematic wiring diagram;

Fig. 11 is a view of the finished rivet and mandrel assembly;

Fig. 12 is a view of a modified form of mandrel gripping arrangement;

Fig. 13 is a plan view of the mandrel gripping arrangement shown in Fig. 12; and

Fig. 14 is a detail view of a set of the jaws employed in the arrangement shown in Fig. 12.

Referring to Figure 1 of the drawing in detail, there is illustrated a side elevational view of an embodiment of this invention in which reference numeral 10 designates a hopper of conventional construction, for receiving a supply of rivets and for arranging the rivets with their heads upright. The rivets are then fed to the slide 11 which is connected to the bottom of the hopper mechanism and conveys the rivets down to the rotary turret 12. The slide 11 comprises a pair of spaced members arranged in side by side relation as shown in the plan view, Figure 2, so that the stem of the rivet extends down between these parallel spaced members and the heads of the rivets extend over the tops of these members while the rivets slide downward thereon.

The turret 12 is attached to a shaft 13 which extends down through the table 14 and is attached to an actuating and brake mechanism that is supported below the table by the bracket 15. This actuating and brake mechanism includes a ratchet wheel 16 and an outer brake drum 17. The ratchet wheel 16 is rotated in step by step fashion by the pneumatically actuated pawl 18 which is attached to a piston that is operatively associated with the cylinder 19 shown in Figs. 3 and 4. The ratchet 16 is attached to the shaft 13 and functions to rotate the turret 12 in step by step fashion so that the rivet-receiving recesses 20 that are positioned around the periphery of the turret 12 are presented one after another to the end 60 of the rivet slide 11 whereby the heads of the rivets 21 are slipped one after another into these recesses which are large enough to receive said heads.

A grooved member 12a extends at least partially around the turret 12 from the lower end of the slide 11 to the rivet threading mechanism positioned diametrically opposite to the slide 11. This grooved member is provided with a groove 12b for receiving the body of the rivets and the heads of the rivets engage and are slid along the top surfaces adjacent to the groove 12b of the member 12a. The turret 12 slightly clears the top of the grooved member 12a as shown in Fig. 2a; however, this clearance is not enough to permit the heads of the

rivets to slide between the turret 12 and the member 12a. Accordingly, the recesses in the turret engage the rivet heads and push the rivets along through the groove 12b toward the rivet threading mechanism. The member 12a is also provided with a flange 12c which extends toward the periphery of the turret 12 and partially overhangs the heads of the rivets.

On the other side of the turret 12 preferably, but not necessarily, diametrically opposite from the slide 11 there is positioned a mechanism including a pneumatically actuated rod 26, that is arranged to press the rivets, one by one as said turret is rotated, into the jaws 24 and 25 as shown in Figs. 3, 5, 6 and 7, thereby threading said rivets on a vertically supported wire member 22. The bottom end of this wire member 22 is provided with an enlarged end portion which, during the rivet threading operation, rests in a cavity formed in the bracket 23. The upper end of this wire member 22 is positioned between the jaws 24 and 25 and these jaws are positioned in a recess in the table 14 and beneath the turret 12 as shown in broken line outline in Figure 4, so that the end of the rod 26 is positioned beneath the recessed periphery of the turret 12. Thus during the operation of this device the turret 12 is rotated in step by step fashion and the rivet guiding recesses are one after another stopped beneath the pneumatically actuated plunger 26. When the turret stops with a rivet guiding recess over the jaws 24 and 25, the rivet in said recess is held therein by the member 12d that is pivoted to the member 12a by the pivot 12f. This member 12d is pressed against the head of the rivet by the spring 12e and the rivet is thus supported over the oval shaped cavity 26a of the jaws 24 and 25 illustrated in Figure 5, and the bottom end of the rivet is aligned with the narrow cavity 26b. The plunger 26 which is attached to the piston 27 of the cylinder 28 is then actuated and the rivet 21 is pressed down between said jaws, thereby causing these jaws to tilt on their pivots 24a and 25a, respectively, as shown in Figure 6. At the same time the arms 24b and 25b which support the jaws 24 and 25, respectively and which in turn are supported on the table 14 by the pivots 24c and 25c, respectively, are caused to open against the tension of the spring 29 as illustrated in Figure 9.

The jaws 24 and 25 are provided with arcuate surfaces 24d and 25d, respectively, near the bottoms thereof, and these surfaces cooperate to hold the rivet-receiving wire member 22 in proper alignment so that the rivet 21 may be threaded over the upper end of this wire member by means of the plunger 26 as shown in Figure 6.

As the rivet 21 is forced downward through the jaws 24 and 25, the bottom parts of these jaws are opened up against the tension of the spring 30, since the head of the rivet 21 causes the jaws to swing on their pivots 24a and 25a as shown in Figure 7, while the spring 29 brings the jaw supporting arms 24b and 25b together. As the head of the rivet 21 slides past the arcuate surfaces 24d and 25d of the jaws, the spring 30 that is attached to suitable pins supported by the jaws, brings said jaws together so that they assume the position shown in Figure 5 after the plunger 26 is withdrawn by the piston 27.

This apparatus is operated by an electrically controlled pneumatic system which will now be described. This system is illustrated schematically in Figure 10 and includes a pair of solenoids 31 and 32 for operating the valves 33 and 34, respectively. The valve 34 is a reversing type that is employed for controlling fluid under pressure to the cylinder 28 so that in one position the valve feeds fluid under pressure to the top of the cylinder 28 and exhausts fluid from the bottom of the cylinder, whereas in the other position the valve 34 feeds fluid under pressure to the bottom of the cylinder 28 and exhausts fluid from the top of this cylinder. Thus the piston 27 may be moved up and down in the cylinder 28 to actuate the plunger 26 as previously described. The

valve 33 is similar to the valve 34 and the solenoid 31 controls this valve 33 to feed fluid under pressure to the front of the piston in the cylinder 19 and exhaust fluid from the back of the piston in one position of said valve and in the other position said valve 33 feeds fluid under pressure to the back of the piston in the cylinder 19 and exhausts fluid from the front thereof.

The solenoid 31 is connected to the battery 35 or other source of current supply through switches 36, 37 and 38 which are connected in series. The switch 36 is supported beneath the table 14 by the bracket 39, and this switch is provided with an actuating lever 40 that is actuated by the pin 41 which is carried by the gear 42. The gear 42 meshes with the gear 43 that is attached to the shaft 13 so that the switch 36 is opened after the turret 12 and shaft 13 are rotated to a predetermined angle whereby the machine may be stopped after a predetermined number of rivets are threaded on to the wire mandrel 22. The switch 37 may be a manually operated switch useful for stopping the machine when desired.

The switch 38 is supported by the support 28a which also supports the cylinder 28 as shown in Figure 3 and this switch, which is normally open, is arranged to be closed by the arm 38a that is carried by the piston rod 26, when the piston 27 is at its uppermost position in the cylinder 28. This switch 38 energizes the actuating coil of a relay 40a which operates to close the circuit of the solenoid 31. The piston of the cylinder 19 moves to the left in Figure 10 to cause an arm 19a, actuated by the piston rod 18 of the cylinder 19, to close the switch 19b so that the circuit of the solenoid 32 is closed and fluid under pressure is admitted to the upper end of the cylinder 28. This brings the piston 27 and rod 26 down to cause opening of switch 38 but the relay 40a remains actuated to retain the circuit of the solenoid valve closed by reason of a locking circuit which is completed through the switch 19c. The rod 26 engages the top of the rivet 21 as shown in Figure 5 and presses this rivet on to the wire mandrel 22. However, when the piston 27 is brought to the bottom of the cylinder 28, the arm 38a shown in Figure 3 engages the switch 19c which is also mounted on the support 28a (Fig. 3), and opens this switch to open the locking circuit of the relay 40a. The relay thus opens the circuit through the solenoid 31 to cause the piston rod 18 to move to the right in Fig. 10 to open the switch 19a to open the circuit of the solenoid 32, thereby allowing the valve 34 to assume its normal position in which it supplies fluid under pressure to the bottom end of the cylinder to return the piston to its upper position, as shown in Figure 3. In this position the lever 38a carried by the piston rod 26 closes the switch 38 and the relay 40a again operates to close the circuit of the solenoid 31 so that this solenoid actuates the pawl 18 and arm 19a, thereby advancing the turret 12 one step and presenting another rivet 21 to the jaws 24-25. The cycle of operation described above is then repeated and the machine continues to feed and assemble rivets on the wire mandrel 22 until the pin 41 (Fig. 4) engages the arm 40 of the switch 36 whereby this switch is opened and the machine stopped after a predetermined number of rivets are assembled on the wire mandrel.

In Figure 11 there is shown an assembly of rivets on the mandrel 22. This mandrel is provided with an enlarged end 22b that is shaped with gradually sloping sides so as to provide an upsetting enlargement which is used for expanding the rivets during the riveting operation, and this enlarged portion is provided to the mandrel before the rivets are assembled thereon. After the rivets are assembled on the mandrel, the other end, 22a, is also provided with an enlargement so that the rivets are retained on the mandrel during shipment and handling. The rivets are not removed from the mandrel over the enlargement 22a since this enlargement is adjacent to the rivet head of the last rivet placed on the mandrel. The

enlargement 22a may be formed or placed on the mandrel in various ways, for example, the end of the mandrel may be enlarged by swaging or by applying pressure to the end surface; on the other hand, enlargement may be formed by applying a suitable amount of adhesive or resin which is adapted to stick to the mandrel and harden. Other materials such as a drop of solder may also be used to form this enlargement.

In Figures 12, 13 and 14 there is illustrated a modified form of mandrel gripping jaws that may be employed in accordance with this invention. In this modification the rivet-receiving mandrel 22 is adapted to be gripped between an upper set of jaws and a lower set of jaws. The upper set is slidably positioned in the frame member 45 and the lower set is slidably positioned in the frame member 46. These frame members are of identical construction and they are each provided with a recess 47 through which the mandrel 22 is inserted. The upper set includes jaws 48 and 49 which are formed with inter-leaving jaw members as shown in Figure 14. Thus the jaw 48 is provided with the member 50 which is adapted to be inter-leaved between the members 51 and 52 of the jaw 49 so that the mandrel 22 may be gripped in the V-shaped recesses formed in these inter-leaving members.

The jaw 49 is provided with an extension 49a to which is pivotally attached a roller 49b. This roller 49b is adapted to engage the eccentric 53 which is attached to the shaft 54 and is rotatable thereby. Another eccentric 55 is attached to the shaft 54 and this latter eccentric is adapted to engage the roller 56 that is pivotally supported on the rod 57 which is attached to the extension 48a of the jaw 48. Thus as the shaft 54 is rotated, the eccentrics 53 and 55 function to slide the jaws into open position against the tension of the springs 58 and 59. These springs are positioned in the frame 45 in suitable recesses so that one end of the spring 58 abuts a surface of the frame and the other end of this spring abuts a projection 48c that is attached to the jaw 48. Likewise, the spring 59 has one end thereof abutting a surface of the frame 45 and the other end abuts the projection 49c that is attached to the jaw 49. As a result, when the eccentric 53 is rotated and causes the jaw 49 to slide into open position against the tension of the spring 59, the eccentric 55 will simultaneously engage the roller 56 and move the jaw 48 into open position against the tension of the spring 58.

A similar set of jaws 60 and 61 is positioned in the frame 46 and these are also arranged to be opened by suitable eccentrics mounted on the shaft 54. The jaws 60 and 61 are arranged to be closed when the jaws 48 and 49 are open and vice versa, so that as rivets such as the rivet 62 are placed upon the mandrel 22 from the turret 12 and associated apparatus previously described, the rivet first rests upon the closed jaws 48 and 49 which also function to hold the mandrel 22 in proper position to receive the rivet; however, before the next rivet is placed upon the mandrel 22, the shaft 54 is rotated by means of a suitable motor (not shown), and the jaws 48 and 49 are open to allow the rivet 62 to fall downward on the mandrel 22. While this is taking place the jaws 60 and 61 are closed to grip the mandrel. After the rivet 62 is released by the jaws 48 and 49, these jaws are again closed to grip the mandrel. From the foregoing description, it is seen that the jaws 48-49 and 60-61 are alternately opened from their mandrel gripping position to allow rivets to pass therebetween downward on the mandrel. This operation is of course timed with the operation of the turret 12, so that jaws operate in step with the feeding of the rivets to the mandrel 22.

While we have shown and described certain preferred embodiments of the invention, it will be apparent that the invention is capable of variation and modification from the form shown so that the scope thereof should be

limited only by the scope of the claims appended hereto.

What we claim is as follows:

1. The method of assembling hollow rivets having a head at one end thereof comprising the steps of arranging a plurality of rivets with their heads in one direction, placing the arranged rivets on a support, supporting a wire underneath said support, rotating the support and the rivets placed thereon in step by step fashion, stopping the rivet support step by step with successive rivets supported thereby over the top of said wire, forcing the rivets one after another from said support onto said wire as said rivets are aligned therewith, and thereafter swaging the end of said wire to prevent the rivets from falling off of the wire.
2. The method of assembling hollow rivets having a head at one end thereof comprising the steps of arranging a plurality of rivets with their heads in one direction, placing the arranged rivets on a support, supporting a wire underneath said support at a predetermined point, rotating the support, stopping the support with a rivet supported thereby over the top of said wire, moving the rivet aligned with said wire onto said wire, continuing the moving of the rivets from said support and onto said wire one after another in step with the rotation of said support until a predetermined number of rivets are placed on said wire, and thereafter swaging the end of said wire to prevent the rivets from falling off of the wire.
3. The method of assembling hollow rivets having a head at one end thereof comprising the steps of arranging a plurality of rivets with their heads in one direction, placing the arranged rivets on a support, supporting a wire underneath said support at a predetermined point, rotating the support, stopping the rivet support with a rivet supported thereby over the top of said wire, moving the rivet aligned with said wire onto said wire, continuing the moving of the rivets from said support and onto said wire one after another in step with the rotation of said support until a predetermined number of rivets are placed on said wire, and thereafter placing an enlargement on the end of said wire over which the rivets were threaded thereon to prevent the rivets from falling off of the wire.
4. An apparatus for assembling hollow-headed rivets comprising a hopper mechanism for receiving a plurality of hollow-headed rivets, said mechanism having means for feeding said rivets with the heads thereof uppermost, means for holding a wire upon which a plurality of said rivets are to be threaded in the same direction, means for transporting said rivets with the heads thereof oriented upward to said last mentioned means, means for rotating said transporting means in step by step fashion, means for periodically stopping said transporting means with a rivet transported thereby in alignment with the top of said wire, means for shifting the rivets from said transporting means onto said wire, and means for operating said shifting means in timed relation with the step by step operation of said transporting means.
5. An apparatus for assembling hollow-headed rivets comprising a hopper mechanism for receiving a plurality of hollow-headed rivets, means for holding a wire upon which a plurality of said rivets are to be threaded in the same direction, means for transporting said rivets with the heads thereof oriented in one direction to said last mentioned means, means for rotating said transporting means in step by step fashion, means for periodically stopping said transporting means with a rivet transported thereby in alignment with the top of said wire, means for pressing said aligned rivet through said wire holding means further onto said wire and means for operating said pressing means in timed relation with the step by step operation of said transporting means.
6. An apparatus for assembling hollow-headed rivets comprising a hopper mechanism for receiving a plurality of hollow-headed rivets, means for holding a wire upon

which a plurality of said rivets are to be threaded in the same direction, means for transporting said rivets with the heads thereof oriented in one direction to said last mentioned means, means for rotating said transporting means in step by step fashion, means for periodically stopping said transporting means with a rivet transported thereby in alignment with the top of said wire, and means for pressing said aligned rivet through said wire holding means further onto said wire.

7. An apparatus for assembling hollow-headed rivets upon a mandrel, comprising means for holding a mandrel upon which a plurality of said rivets are to be threaded in the same direction, means for arranging a plurality of rivets in a file with the heads thereof oriented in one direction, and means for feeding the rivets from said file to said mandrel, said means for holding the mandrel comprising pivoted jaw means adapted to be opened to permit rivets to be pressed therethrough on said mandrel.

8. An apparatus for assembling hollow-headed rivets upon a mandrel, comprising means for holding a mandrel upon which a plurality of said rivets are to be threaded in the same direction, means for arranging a plurality of rivets in a file with the heads thereof oriented in one direction, and means for feeding the rivets from said file to said mandrel, said means for holding the mandrel including a pair of pivotally supported members to which the jaw means are pivoted.

9. An apparatus for assembling hollow-headed rivets upon a mandrel, comprising means for holding a mandrel upon which a plurality of said rivets are to be threaded

10

15

20

25

30

in the same direction, means for arranging a plurality of rivets in a file with the heads thereof oriented in one direction, and means for feeding the rivets from said file to said mandrel, said means for feeding the rivets to the mandrel comprising a rod for pushing the rivets on said mandrel, and pneumatic means for actuating said rod.

10. An apparatus for assembling hollow-headed rivets upon a mandrel, comprising means for holding a mandrel upon which a plurality of said rivets are to be threaded in the same direction, means for arranging a plurality of rivets in a file with the heads thereof oriented in one direction, means for moving said file of rivets to said mandrel, and means for feeding the rivets from said file to said mandrel.

11. An apparatus for assembling hollow-headed rivets upon a mandrel, comprising means for holding a mandrel upon which a plurality of said rivets are to be threaded in the same direction, means for arranging a plurality of rivets in a file with the heads thereof oriented in one direction, means for moving said file of rivets to said mandrel, and means for feeding the rivets from said file to said mandrel, said means for moving said file of rivets including pneumatic means for the actuation thereof.
